UNITED STATES PATENT OFFICE.

ERNEST GOODALL NICHOLSON, OF SOUTH EALING, LONDON, ENGLAND, ASSIGNOR TO THE AEOLIAN COMPANY, LIMITED, OF LONDON, ENGLAND.

TRACKING MECHANISM FOR AUTOMATIC MUSICAL INSTRUMENTS.

Application filed December 4, 1923. Serial No. 678,492.

To all whom it may concern:

Be it known that I, ERNEST GOODALL NICHOLSON, a subject of the King of Great Britain and Ireland, residing at 2 Radbourne Avenue, South Ealing, London, W. 5, England, have invented certain new and useful Improvements Relating to Tracking Mechanism for Automatic Musical Instruments, of which the following is a specification.

This invention relates to automatic musical instruments operating under the control of a tune sheet and provided with means whereby lateral deviation of the tune sheet is automatically overcome by readjustment of the tune sheet in relation to the tracker bar, so that the alignment of the perforations in the tune sheet with the note ducts in the tracker bar is automatically maintained. The means which have been proposed for this purpose, consist, among others, in the provision of two pairs of control ducts in the tracker bar in positions corresponding to two widths of tune sheet, so that when the tune sheet is disposed normally with respect to the note ducts in the tracker bar, the said pairs of ducts or the inner pair of ducts respectively, according to the width of the tune sheet in use, are covered, but on the tune sheet deviating from the normal position one duct of the pair of ducts corresponding to the width of the tune sheet is uncovered to admit air, whereby primary valves controlling the mechanism are adjusted and determine the operation of the mechanism for the readjustment of the tune sheet in relation to the tracker bar. The ducts of one pair of control ducts are respectively connected to the primary valve casings by passages or conduits fitted with means whereby communication through them may be interrupted as the result of the admission of air through the ducts of the other pair of control ducts. The present invention is directed to an improvement in such tune sheet adjusting mechanism whereby it is rendered effective in use with tune sheets of standard width, or of widths greater or less than standard width, or tune sheets which have expanded or contracted in width as the result of climatic or other conditions.

According to the invention the tracker bar is provided with three or more pairs of

control ducts, the ducts of each pair being disposed at a distance apart corresponding to a particular width of tune sheet and each pair serving for a different width of tune sheet, and the said control ducts are adapted to determine the adjustment of primary valves controlling the operation of the mechanism serving to re-establish the normal disposition of the tune sheet with reference to the tracker bar, and are so provided that only that pair of which one is uncovered as the result of lateral movement of the tune sheet is effective to determine the necessary adjustment of the primary valves.

Certain of the control ducts, when uncovered by the tune sheet, are adapted to admit air to one or other of two chambers, cylinders or the like provided with diaphragms, pistons or the like for effecting the movement of the primary valves and for this purpose the ducts of one pair of the control ducts, for example, the pair corresponding to the narrowest width of tune sheet, may be respectively in communication directly with the said chambers or the like, while the ducts of the other pairs either communicate with the said chambers or the like by passages adapted to be interrupted, or serve to admit air by which the interruption of the passages from the other ducts is effected. The control ducts may conveniently be connected with a junction block or blocks formed with chambers or recesses provided with flexible diaphragms, pistons or the like which, upon the admission of air at one side, serve to close or interrupt the passage for air from one of the control ducts to the primary valve chambers or the like.

The mechanism effecting relative movement of the tune sheet and tracker bar under the control of the said ducts conveniently comprises a pneumatic actuating device adapted to move the tune sheet or music roll and the take-up spool in the axial direction by such means as cams. Other means for effecting the relative movement of the tune sheet and/or tracker bar, however, may be provided.

The invention further comprises the constructional features hereinafter described and claimed.

The invention is illustrated by way of example in the accompanying drawings.

Figure 1 represents, diagrammatically and

in part section, tune sheet adjusting mechanism provided in accordance with the invention.

Figure 2 is a corresponding plan view.

5 Figure 3 is an elevation of the junction block to an enlarged scale.

Figures 4 and 5 are respectively sections on the lines A—A, B—B, of Figure 3.

In carrying the invention into effect according to the construction illustrated in the accompanying drawings, a tracker bar *a* of the usual construction is provided and there are formed therein, in positions determined by the disposition of the lateral edges of 10 tune sheets *b* of particular widths, when normally disposed in relation to the tracker bar, pairs of control ducts *c d*, *e f*, *g h*, the pair of ducts *c d* being disposed at a greater distance than the pair of ducts *e f*, while similarly 15 the ducts *e f* are disposed at a greater distance apart than the ducts *g h*. Thus, the ports *e f* are adapted to co-operate with a music sheet of the standard English width of $11\frac{5}{16}$ inches while the ports *c d* will co-operate with a sheet which has become expanded in width or is cut to a greater width. Similarly 20 the ports *g h* will co-operate with a music sheet which is cut to a reduced width, such as the standard American roll which has a width of $11\frac{3}{32}$ inches or with a music sheet which has become contracted in width. The control ducts are connected with a junction block *i* by means of tubes *c¹*, *d¹*, *e¹*, *f¹*, *g¹*, *h¹* respectively. The junction block *i* is provided with a chamber *i¹*, in the opposing walls of which there are respectively formed pairs of recesses *j*, *k*, *l*, *m*, conveniently of circular form, the recesses *j k* being smaller in area than the recesses *l m*. The said recesses are separated from the chamber *i¹* by flexible diaphragms *j¹* *k¹* *l¹* *m¹*. The tubes *c¹* *d¹* are respectively connected with passages *c²* *d²* in the junction block *i* which open respectively into the recesses *j k* at the centres thereof. The bottom of each of the said recesses is advantageously of convex form in cross-section so that the diaphragms *j¹* *k¹* under certain conditions may serve to close the outlet orifices 25 of the passages *c²* *d²*. The diaphragms *j¹* *k¹* are advantageously fitted with pallets *j²* *k²*. The tubes *e¹* *f¹* are respectively connected with passages *e²* *f²* respectively in the junction block *i* leading respectively to the recesses *m l*. It will be observed that while the control duct *c* is connected by the tube *c¹* to the recess *j* the control duct *e* is connected by the tube *e¹* to the recess *m* and not to the recess *l*. Similarly the control duct *d* is connected to the recess *k* while the duct *f* is connected to the recess *l*. The tubes *g¹* *h¹* are respectively connected with passages *g²* *h²* formed in the junction block *i* and connected with outlet passages *i²* *i³* with which the recesses *j* and *k* also communicate by way

of the passages *j³* *k³*. The passages *i²* *i³* are respectively connected by conduits *n¹* *o¹* with the casing *q* of the primary valves *n*, *o*, controlling the operating mechanism for effecting lateral movement of the tune sheet in the manner hereinafter described. The chamber *i¹* is connected by a passage *i⁴* with a conduit *i⁵* leading to the main suction system so that the chamber *i¹* may be subjected to a vacuum for the purpose of drawing the diaphragms *j¹* *k¹* *l¹* *m¹* in directions from the respective recesses. 70

The primary valve casing *q* is provided with a chamber *q¹* communicating by a conduit *q²* with the main suction system. At the bottom of the chamber *q¹* there are formed recesses *n²* *o²*, closed by diaphragms *n³* *o³* and provided with passages by which the respective conduits *n¹* *o¹* may be put into communication with the said recesses *n²* *o²*. 80 Suitable bleed hole communication between the recess *n²* *o²* and the main suction system is also provided as indicated at 1 in Fig. 1 of the drawings. The primary valves *n*, *o*, which are respectively disposed contrally above the diaphragms *n³* *o³* are provided with stems *n⁴* *o⁴* which extend upwardly through clearance passages *n⁵* *o⁵* formed in the upper plate of the casing *q*. The stems *n⁴* *o⁴* also carry valve plates *n⁶* *o⁶* adapted to seat upon the exterior of the upper plate of the casing *q*. 90

The passages *n⁵* *o⁵* are connected respectively through suitable conduits with passages *n⁷* *o⁷* formed in the centre board *r* of two operating bellows or pneumatics *r¹* *r²* the movable boards of which are connected together by means of rods *r³* so that when one of the pneumatics *r¹* or *r²* closes the other opens. 100

In order to permit lateral adjustment of the tune sheet *b* the tune sheet or music roll *s* and the take-up spool *t* are each mounted to be laterally movable in the tracker box *a¹*. Thus the left hand clutch *s¹* of the tune sheet or music roll *s* is rotatably fitted upon a longitudinally movable spindle *s²* carried in a bearing *a²* on the tracker box while the right hand clutch *s³* is fixedly mounted upon the spindle *s⁴* carrying the brake disc and re-roll sprocket wheel and mounted so as to be longitudinally movable in a bearing bracket *a³* secured to the side of the tracker box *a¹*. Similarly the spindle *t¹* of the take-up spool *t* is slidably carried within a bearing bracket *a⁴* at the left hand side of the tracker box while the clutch *t²* is mounted upon a longitudinally movable spindle *t³* carrying the driving sprocket wheel and mounted to slide longitudinally in the tracker box and a bracket *a⁵*. A vertically disposed spindle *u* is mounted in the plane of the spindles of the tune sheet or music roll and the take-up spool in a footstep bearing *u¹* and a bracket *u²* fitted to the bracket 110

115

120

125

130

s^3 . The said spindle u carries fixedly mounted upon it cams s^5 t^4 adapted respectively to engage the extremities of the spindles s^4 t^3 . The cam s^5 is provided with an arm or lever s^6 which is connected with the movable board of the pneumatic r^2 by means of a rod r^4 formed in two parts connected by means of a double threaded nut and lock nuts r^5 in order that adjustment of the length many be effected. A spring s^7 is connected between the bearing a^2 and a collar upon the spindle s^2 for the purpose of causing the tune sheet or music roll to follow the cam s^5 while similarly the spindle t^1 of the take-up spool bears against a leaf spring t^5 serving to press the spool in the direction of the cam t^4 .

The operation of the mechanism illustrated in the drawings is as follows:—Assuming that the tune sheet is of a width such that it covers the control ducts c d when it is in the normal position and that both ducts are covered, no air is admitted to the recesses n^2 o^2 of the primary valve casing q and the valves n o remain in the lowermost position so that the bellows r^1 r^2 are subjected to the suction applied at q^2 and remain in the central or neutral position, in balance. When, however, the tune sheet moves so as to uncover the duct c , air passes by way of the tube c^1 to the recess j of the junction block i and, since suction is applied to the chamber i^1 and the diaphragm j^1 is drawn outwardly from the recess j , the air can pass by the passages j^3 and i^2 and tube n^1 to the recess n^2 . The diaphragm n^3 is therefore lifted under the suction and raises the valve n to cut off the suction from the passage n^5 and to open the said passage to the atmosphere by the lifting of the valve plate n^6 . Air thus passes by the passage n^7 into the bellows r^1 . The bellows r^2 therefore closes under the suction and operates the cams s^5 , t^4 through the rod r^4 to move the tune sheet or music roll s and take-up spool t to the left hand so that the tune sheet is returned to the normal position covering the port c . Similarly when the tune sheet uncovers the control duct d air passes through the path represented by the tube d^1 , recess k , passages k^3 and i^3 , tube o^1 to the recess o^2 , so that the diaphragm o^3 rises, lifting the valve o and admitting air below the valve plate o^6 to the passage o^7 . The bellows r^1 therefore closes and the cams s^5 t^4 are moved to permit a movement of the tune sheet or music roll s and take-up spool t to the right under the action of the springs s^7 and t^5 .

In the case of a music sheet of a width corresponding to the spacing of the ducts e f , when the tune sheet is in the normal position the exposure of the ports c d does not result in any movement of the mechanism for the reason that air is admitted simultaneously by way of the tubes c^1 d^1 through the paths hereinbefore described so that both the diaphragms n^2 and o^2 are effective to lift the valves n o and thus to place the bellows r^1 and r^2 both in communication with the atmosphere so that they remain in balance. When, however, the tune sheet moves laterally and exposes the duct e , air is admitted by way of the tube e^1 to the recess m with the result that the diaphragms m^1 k^1 are thrown over and the admission of air from the passage d^2 into the recess k is interrupted. The diaphragm o^3 in the primary valve box is therefore permitted to fall and with it the valve o so that the bellows r^2 is subjected through the passage o^7 to the suction applied through q^2 to the chamber q^1 and communication with the atmosphere is interrupted by the fall of the valve plate o^6 . Thus the bellows r^2 closes and the tune sheet is moved to the left in the manner described. Similarly in the case when the tune sheet moves to uncover the control duct f the balance of the bellows r^1 r^2 is destroyed by the falling of the diaphragm n^3 and with it the valve n so that the bellows r^1 is subjected through the passage n^7 to the suction applied at q^2 to the chamber q^1 and communication with the atmosphere is interrupted by the fall of the valve plate n^6 . The bellows r^1 therefore closes and the tune sheet is moved to the right to cover the control duct f in the manner hereinbefore described.

In the case where the tune sheet is of a width corresponding to the distance between the outer edges of the control ducts g and h and when in the normal position uncovers the control ducts c d e and f , the mechanism remains inoperative by reason of the fact that the bellows r^1 r^2 are again in balance. This is due to the fact that the admission of air by both of the ducts e and f results in the simultaneous throwing over of the pairs of diaphragms j^1 l^1 k^1 m^1 so that the passage of air through both tubes c^1 and d^1 to the tubes n^1 and o^1 is interrupted and therefore both the diaphragms n^3 and o^3 remain in the lowermost position so that the valves n o permit the suction applied at q^2 to act equally through the passages n^7 o^7 upon the bellows r^1 r^2 . When, however, the tune sheet moves laterally to uncover the control duct g , the air admitted passes by way of the tube g^1 and the passage g^2 to the tube n^1 so that the valve n is lifted and air can pass below the valve plate n^6 into the passage n^7 to the bellows r^1 . The bellows r^2 then closes and the tune sheet is moved to the left again to cover the duct g . Similarly when the tune sheet moves to the left to uncover the duct h , air passes by way of the tube h^1 to the passage h^2 and thence by way of the tube o^1 to the recess o^2 so that the valve o is lifted to admit air to the bellows r^2 . The

bellows r^1 then closes and the tune sheet is moved to the right again to cover the duct h .

It will be understood that the invention is not limited to the particular construction of the parts of the mechanism hereinbefore described and illustrated as these may be clearly varied without departing from the invention. Thus the control ducts may be 10 formed if desired within a separate tracker bar provided especially for the purpose. Again, the primary valves n , o may serve to control the action of any suitable construction of mechanism having for its purpose to secure the normal disposition of the tune sheet with reference to the tracker bar.

I claim:

1. Tracking mechanism for automatic musical instruments operating under the 20 control of a tune sheet and provided with means whereby upon lateral deviation of the tune sheet the exposure of a control duct results in the operation of mechanism serving to re-establish the normal disposition 25 of the tune sheet with reference to the tracker bar, wherein a plurality of pairs of control ducts are provided each pair of which corresponds to a particular width of tune sheet, the said pairs of control ducts 30 being so provided that only that pair of which one duct is uncovered as the result of lateral movement of the tune sheet is effective to determine the re-adjustment of the tune sheet with reference to the tracker 35 bar, substantially as described.

2. Tracking mechanism for automatic musical instruments as set forth in claim 1, wherein the ducts of one pair of the control ducts directly communicate uninterrupted 40 with chambers, having diagrams 40 for effecting movement of primary valves, substantially as described.

3. Tracking mechanism for automatic musical instruments as set forth in claim 1, and having certain ducts of the pair of control ducts in communication with the primary valve chambers by passages adapted 45 to be interrupted upon exposure of other control ducts, the said interruption of the passages being nullified upon the exposure 50 of yet other control ducts, substantially as described.

4. Tracking mechanism for automatic musical instruments as set forth in claim 1, having oppositely disposed chambers fitted 55 with diaphragms subjected to suction, one of said chambers affording communication between a duct of one pair of control ducts and a primary valve casing subject to interruption by the corresponding diaphragm, 60 and the other chamber communicating with a duct of another pair of control ducts, wherein the second of the said chambers is of larger area than the first and the corresponding diaphragm is enabled to overpower the diaphragm of the first chamber on the admission of air to the said second chamber, substantially as described. 65

ERNEST GOODALL NICHOLSON.
